CHARLES T. COE, OF KEARNEY, NEW JERSEY.

COMPOUND TWO-STAGE TURBINE.

1,301,387.

Specification of Letters Patent. Patented Apr. 22, 1919.

Application filed March 6, 1916. Serial No. 82,368.

To all whom it may concern:

Be it known that I, CHARLES T. COE, a citizen of the United States, and resident of Kearney, in the county of Hudson and State 5 of New Jersey, have invented certain new and useful Improvements in Compound Two-Stage Turbines, of which the following is a specification.

This invention relates to a compound two stage turbine. The drawings represent the turbine with a fan blower for the purpose of explanation.

Figure 1 represents a front elevation of the turbine with a partial section as on the line 1, 1, of Fig. 2; Fig. 2 shows a section as on the line 2, 2 of Fig. 1; Fig. 3 shows a fragmentary longitudinal section of a modification of the turbine; Fig. 4 shows a section as on the line 4, 4 of Fig. 3; Fig. 5 is a section as on the line 5, 5 of Fig. 1; Fig. 6 shows a section as on the line 6, 6, of Fig. 1 and Fig. 7 shows a partial section as on the line 7, 7 of Fig. 4.

The casing of a turbine is cup shaped and 25 is indicated in its entirety by the numeral 20. The rear wall 21 of the casing has formed therewith the concaved portion 22. The casing 20 has extending from its outer circumferential surface the pairs of nozzle 30 supports 24 and 25 the longitudinal axes of which are tangential to a circle passing through the middle portion of the outer row of buckets to be described. Valve chambers 26 are formed at the upper ends of the supports 24, 25. Nozzles 27 are located in the supports 24 and 25 and the upper ends of said nozzles form the valve seats 28. A valve casing 30 is in threaded engagement with the upper end of each support 24 and 40 carries a valve spindle 31 for the needle valve 32. A hand wheel 33 is supported at the upper end of the spindle 31. The valve chambers 26 of each pair of nozzle supports 24 and 25 are connected by the connecting conduit 36. The valve chambers 26 of the nozzle supports 24 are connected by 45 the piping 38, which has extending therefrom the main inlet pipe 40 with the inlet valve 41.

50 An exhaust cavity 42 is formed with the casing 20 and has extending therefrom at one side the exhaust piping 43 and at the other side is attached the relief valve 44. A foot 45 with the flange 46 extends from 55 the lower portion of the rear wall 21. Lugs

47 extend from the cylindrical surface of the casing 21. The depressed portion 22 of the rear wall 21 has extending outwardly therefrom the sleeve 48 and the latter has formed therewith the vacuum or exhaust 60 chamber 50. On the inner face of the rear wall 21 of the casing is formed an annular lug 51 that supports a row of stationary buckets to be described.

The shaft of the turbine is indicated at 65 5 with the collar 56. A gland 57 with the flange 58 and made of a soft alloy, preferably what is commercially known as Allen metal is carried on the shaft 55 and one end abuts against the collar 56. A slot 59 is 70 formed in the gland 57 and a pin in the shaft 55 engages said slot so that the gland 57 will rotate with the shaft 55. An annular collar 60 is fastened in a cavity in said depressed portion 22 over the gland 57. A 75 tight joint is made between the abutting surfaces of the gland 57 and the collar 56. A clearance of about one thousandth of an inch is made between the collar 60 and the gland 57. Against the shoulder 61 of the 80 shaft 55 there abuts a gland 62 similar to 57 and which forms a tight joint with the wall 63 of the sleeve 48. A ball bearing cage 68 abuts with one end face against the accompanying end of the gland 62. Ball bearings 85 69 are carried in said cage. A spacing ring 70 is located in the sleeve 48 between the gland 62 and the cage 68. One thousandth of an inch clearance is provided between the gland 62 and the spacing ring 70. A 90 screw gland 72 is in threaded engagement with the sleeve 48, and has formed therewith the annular groove 73 for the fibrous packing 74. The sleeve 48 with the gland 72 forms a stuffing box for the shaft 55. A 95 sleeve 75 is tightly secured to the shaft of the turbine and at one end abuts against the cage 68. A grease cup 76 is secured in an opening 77 in the sleeve 48, and the said opening extends to the sleeve 75. A pipe 80 100 extends from the upper end of the chamber 50 and which has connected thereto the piping 81. A pipe 82 extends from the lower end of the chamber 50 and has connected thereto the piping 83.

To the outer face of the rear wall of the casing 20 is bolted a bracket with the ring portion 90 and the arms 91, 92. The latter support the hub 93 of an outer bearing. On the shaft 55 is secured the ball bearing 110

cage 94 with the ball bearings 95 which are shown within the said hub 93. The cage 94 abuts with one edge against the sleeve 75. A screw gland 96 with an annular groove 97 is in threaded engagement with the hub 93. A fibrous packing ring 98 is located in the groove 97. A grease cup 99 is secured in an opening 100 which extends to the sleeve 75. An annular channel 101 with the fibrous 10 packing ring 102 is formed in the hub 93. A sleeve 103 on the shaft 55 abuts with one edge against the shoulder 104 of the shaft 55.

To the front face of the casing 20 is bolted the bonnet 105 which has formed 15 therewith the hub 106. Ribs 107 extend between the hub 106 and the bonnet 105. A vacuum or exhaust chamber 108 is formed in the hub 106.

A gland 115 similar to 57 in the hub 106 20 is supported on the shaft 55 and bears against a shoulder 116 of said shaft and wall 106^a of the hub 106. A ball bearing cage 117 with ball bearings 118 is secured to the shaft 55 and bears against the accompanying 25 edge of the gland 115. A filler ring 120 is located between the ball bearing cage 117 and the gland 115. A nut 121 on the shaft 55 bears against the cage 117. A cap 122 is bolted to the hub 106. A grease cup 123 is 30 secured in an opening 124 formed in the hub 106.

A pipe 125 extends from the upper end of the chamber 108 and has extending therefrom the piping 126. A pipe 127 extends 35 from the lower end of the chamber 108 and has extending therefrom the piping 128.

A gland 129 of Allen metal as described is supported on the shaft 55 in a cavity 130 in the hub 106. A pin 131 extends from 40 said shaft and engages the slot 132 in said gland 129. A ring collar 133 is fastened to the hub 106 over the gland 129. A clearance of one thousandth of an inch is formed between the cylindrical surface of the gland 45 129 and cavity 130. A pair of impeller or turbine wheels are indicated in their entirety by the numerals 134 and 135. These wheels are similar so one only will be described. The wheel has the boss 136 which 50 is fastened to the shaft 55 and has extending therefrom the disk 136^a. Adjacent to the outer end of the disk are similar annular projections 137 and 137^a. A ring 138 is cast opposite the projections 137 and may be connected thereto by the connecting members 139. A ring 140 is cast opposite the 55 projections 137 and may be connected thereto by the connecting members 141. Spokes 142 connect the ring 140 with the hub 136. 60 An outer row of curved buckets 145 with dovetailed ends preferably of steel or other suitable material are placed in the mold when the wheel is cast, between the projections 137 and the ring 138. An inner row 65 of curved buckets 146 similar to the buckets

145 is similarly located between the projections 137^a and the ring 140.

To the annular lug 51 is secured the double annular frame 150 with the members 151 and 152 which are connected by the connecting braces 153. The frame 150 is bolted to the lug 51 by means of the bolts 154. With the frame 150 are cast the curved intermediate stationary buckets 155 of steel or other suitable material and which are reversed to the buckets 145 and 146. With the bonnet 105 is cast the annular lug 159 similar to 51. A double annular frame 160 similar to 150 is secured to the lug 159 by means of the bolts similar to 154. Steel 75 buckets or the like 165 similar to 155 are cast with the frame 160.

Referring to Figs. 3 and 4, the turbine wheel is modified by the substitution of one wheel for a pair of wheels with buckets on its opposite faces. In this instance the wheel or impeller is shown with the boss 168 from which extends the disk 169, which is stepped with the annular flanges 170, 171, 172. Upon each of the flanges 170 is located a ring 175, which is dovetailed for a row of outer buckets 176 which are preferably of steel or other suitable material and are placed in the mold when the ring is cast. At intervals plugs 177 project from the 90 rings 175 and bolts 178 clamp the said rings to the disk 169. Between the flanges 171, 172 are supported rings 180 similar to 175, with the buckets 186. Plugs 187 similar to 177 are secured in place by means of the 95 bolts 188. To the rear wall 21 of the casing 20 of the modification and the bonnet 105 are respectively connected the buckets 155 and 165 as already described.

An air duct 190 has extending therefrom the lug 191. The latter is bolted to the flange 46 by means of the bolt 192. Lugs 195 are cast on the outer surface of the duct 190. Separator pipes 196 are located between the lugs 47 and the lugs 195 and bolts 110 198 extend through the pipes 196 and clamp the duct 190 in place.

A fan wheel 200 is secured to the shaft 55 by means of a nut 201 in the usual way.

To operate the turbine, the driving fluid, 115 in this instance steam, is admitted into the piping 38 through the inlet valve 41. From thence the fluid enters the valve chambers 26 of the pairs of nozzle supports 24 and 25. With the opening of the valves 32 the fluid enters the nozzles 27, and from thence impinges against the outer rows of curved buckets 145. From the latter the driving fluid flows through the stationary intermediate reversed buckets 155 and 165. The 120 driving fluid then impinges against the inner row of curved buckets 146 and from the latter flows into the exhaust cavity 42 to be discharged by the exhaust piping 43. The 125 expansive effect of the driving fluid is uti- 130

lized by flowing from the outer buckets, through the stationary intermediate buckets and then into the inner row of buckets. The energy in the steam as it leaves the outer 5 rows of buckets 145 is utilized in the inner rows of buckets 146.

The glands 57 and 62, make efficient tight joints between the hub of the impeller 135 and the ball bearing cage 68. The clearances between the gland 57 and collar 60, 10 collect any leakage of condensed moisture, and by virtue of centrifugal force due to the rotation of said gland 57 water tight joints are maintained in said clearances. For a 15 similar reason water tight joints are maintained between the gland 62 and spacing ring 70, between the gland 129 and the hub 106, between the gland 115 and hub 106.

Any moisture that may escape past the 20 glands 57 and 62 is deposited into the exhaust or vacuum chamber 50. From the latter moisture is discharged by the piping 81 and 83, by virtue of the suction produced in said piping with the flow of air in the duct 25 190, caused by the rotations of the fan wheel 200. Any moisture that may escape past the glands 115 and 129 is deposited into the exhaust or vacuum chamber 108 and from the latter is discharged by the piping 126 and 30 128 due to the effect of the rotations of the fanwheel 200. By the use of the glands as described the ordinary usual stuffing boxes for the shaft 55 of the turbine are obviated, and the roller bearings 69 and 118 of the 35 shaft 55 are maintained moisture proof.

Having described my invention what I desire to secure by Letters Patent and claim is:

1. In a turbine the combination of a casing 40 an impeller in the casing, a stuffing box for the casing, a vacuum chamber for the stuffing box, a duct spaced from the casing, piping leading from the stuffing box into said duct, a shaft for the impeller extending through the casing, the stuffing box and into the duct, and a fan wheel in the duct fastened to said shaft.

2. In a turbine the combination of a casing, an impeller in the casing, a sleeve 50 formed with the casing, a duct for the casing, a shaft for the impeller extending into the casing, through the sleeve and into the duct, a vacuum chamber formed in the sleeve extending to the shaft, a conduit extending from the vacuum chamber to said duct, a gland surrounding the shaft and turning therewith in the sleeve on each op-

posite side of the chamber and a fan wheel in the duct fastened to the shaft.

3. In a turbine the combination of a casing, 60 an impeller in the casing, a sleeve formed with the casing, bolts extending from the casing, a duct supported on the bolts, a shaft for the impeller extending through the casing, sleeve and into the duct, 65 a vacuum chamber formed in the sleeve extending to the shaft, a conduit extending from the vacuum chamber into the duct, a gland surrounding the shaft and turning therewith in the sleeve on each opposite side 70 of the chamber and a clearance space between each gland and the sleeve to maintain portions of the fluid used in the turbine and which has been condensed in said clearance space, said condensed fluid being 75 maintained in the clearance spaces by the centrifugal force due to the rotations of the impeller.

4. In a device the combination of a casing 80 having a sleeve formed therewith, a bonnet for the casing having a sleeve formed therewith, a duct spaced from the casing, a shaft extending through the casing, both of said sleeves and into the duct, an impeller in the casing and fastened to the shaft, a bearing in each of said sleeves for said shaft, a vacuum chamber in each sleeve coacting with its accompanying bearing to maintain the latter moisture proof, piping extending from the vacuum chamber into the duct and 85 a fan wheel in the duct fastened to the shaft.

5. In a device the combination of a casing 90 having a sleeve formed therewith, a bonnet for the casing having a sleeve formed therewith, a duct for the device, a shaft extending through the casing and both of said sleeves, an impeller in the casing and fastened to the shaft, a vacuum chamber in each sleeve extending to said shaft, piping 95 extending from said chambers to the duct, a pair of glands in each sleeve on opposite sides of its vacuum chamber, a bearing at the outer end of each sleeve for said shaft separated from its accompanying vacuum chamber by one of said glands and a fan wheel in said duct fastened to said shaft.

Signed at the borough of Manhattan in the county of New York and State of New York this 1st day of March, A. D. 1916.

CHARLES T. COE.
